[57] **CLAIM**

The ornamental design for a synthetic foam pillow, as shown and described.

DESCRIPTION

FIG. 1 is a top side perspective view of a synthetic foam pillow, showing our new design;

FIG. 2 is an end view thereof, the opposite end being substantially identical;

FIG. 3 is a side elevational view thereof, the opposite side being substantially identical;

FIG. 4 is a top plan view thereof; and,

FIG. 5 is a bottom plan view thereof.

The convoluted pattern is fragmentarily shown in FIG. 1 for ease of illustration and is understood to extend throughout the areas represented.
